(57) **CLAIM**

The ornamental design for an electric connector, as shown and described.

DESCRIPTION

FIG. 1 is a top plan view;

FIG. 2 is a front elevation;

FIG. 3 is a rear elevation;

FIG. 4 is a bottom plan view;

FIG. 5 is a right-side elevation;

FIG. 6 is a perspective view; and,

FIG. 7 is an auxiliary figure of the connector shown in use, in which the subject article having eight electrical wire ends secured thereto is fitted in a mating connector.

The broken lines showing the mating connector and the electrical wire ends in FIG. 7 are included for the purpose of illustrating environmental structure only and form no part of the claimed design.
